United States Patent Office.

JOHN A. BRADSHAW AND WILLIAM H. BROWN, OF LOWELL, MASSACHUSETTS,
ASSIGNORS TO THEMSELVES AND DARIUS WHITHEAD, OF SAME PLACE.

Letters Patent No. 95,189, dated September 28, 1869.

IMPROVEMENT IN LIQUID-METERS.

The Schedule referred to in these Letters Patent and making part of the same

To all whom it may concern:

Be it known that we, JOHN A. BRADSHAW and WILLIAM H. BROWN, both of Lowell, in the county of Middlesex, and State of Massachusetts, have invented new and useful Improvements in Water-Meters; and we do hereby declare that the following is a full and exact description thereof, reference being had to the accompanying drawings, and to the letters of reference marked thereon.

The nature of our invention consists in the arrangement and construction of the meter, its several parts being enclosed within a metallic case.

To enable others skilled in the art to make and use our invention, we will proceed to describe its construction and operation.

Figure 1 represents a perspective view of our improved water-meter, with a part of the shell removed.

Figures 2, 3, 4, and 5, represent details of the principal working-parts.

Similar letters in the different figures indicate corresponding parts.

In the construction of our improved device, *a* represents the case or shell, into which are placed and secured the working-parts of the same, this shell *a* being provided, at its bottom, with an orifice, *b*, for the discharge of the fluid or water measured.

The top, or cover *c*, of this shell *a*, is provided with an opening, through which passes the inlet, or supply-pipe *d*, which connects with the top part of the plate *e*, this plate *e* being connected to the bottom-plate, or base *f*, by means of screws.

Formed in the centre of the plate *e*, on its under side, is a concave recess, *g*, into which is placed the strainer *h*, as shown in fig. 2 of the drawings, its object being to prevent any sediment from passing through the meter from the supply-pipe *d*.

i is the conductor, which is secured to the base *f*, and connects with the concave recess *g*.

This conductor *i* is provided with one or more spouts or conveyers *j j*, they being located so as to discharge and convey all the water or fluid directly on to the body of the buckets *k k*, which passes through the meter.

These buckets *k k* are formed straight or concave, as desired, on the wheel *l*, as shown in figs. 1 and 3 of the drawings, which is constructed from a light and thin metal, as will give sufficient strength to the same, necessary for the required operation.

This wheel *l* is secured to the shaft *m*, which is furnished with bearings at each end formed in suitable stands, they being secured to the under side of the plate or base *f*.

Located and secured near one end of the shaft *m* is the worm-gear *n*, which connects with the gear *o*, said gear *o* being secured to the vertical shaft *p*, its lower bearing mounted in a suitable stand, which is secured

to the underside of the plate *f*; the other end of said shaft *p* passing through the base *f* and plate *e*, which forms a bearing for the same, and receives the catch-pinion *q*, which is secured to the same.

This catch-pinion *q* connects and gears into the catch-gear *r*, as occasion requires, which is provided with a quill, *t*, and mounted on a stud, *s*, which stud is secured to the plate *e*, this quill *t* passing through the cover *c* of the shell *a*, on which is secured the pointer or hand *u*.

Formed on the cover *c*, directly in under this pointer *u*, is a dial-face, which is suitably divided, figured, and marked in the required divisions.

The conductor, as shown in fig. 4 of the drawings, is provided with a regulating-valve, *v*, which may be worked, laterally, alternately, as occasion may require, by the operator, by aid of the adjustable screw *w*, the object of this valve *v* being to determine and fix the amount of water discharged, so as to correspond with the figures on the dial.

Our improved device being constructed as herein described, and the several parts adjusted in position, is then ready for use.

The water is then let into the supply-pipe *d*. From thence it passes through the strainer *h*, thus arresting all particles of dirt or sediment that it may contain; thence it passes into and through the conductor *i*, and discharged from the same through the spouts *j j* on to the buckets *k k*, and thence through the discharge-orifice *b*.

The force and weight of the water cause the wheel *l* to revolve, in proportion to that force or weight, which motion of the wheel *l* is communicated to the pointer *u* by means of the worm *n*, and gear *o*, catch-pinion *q*, and catch-gear *r*, the pointer *u* indicating on the dial the amount of water discharged from the orifice *b*; the wheel *l*, with the buckets *k k*, being so light, nicely arranged, mounted, and so sensitive that the least action of water, being less or great on the same, will give corresponding action and motion to the wheel *l*, which is communicated to the pointer *u* through the different devices, thus indicating or pointing out on the dial the quantity of water that passes through the meter.

Thus we are enabled to furnish a meter which is compact, simple, cheap, and durable.

What we claim as our invention, and desire to secure by Letters Patent, is—

The arrangement and construction of the case *a*, cover *c*, plates *e* and *f*, strainer *h*, conductor *i*, with one or more spouts *j j*, regulating-valve *v*, and wheel *l*, with buckets *k k*, all when combined and operating as described and specified.

JOHN A. BRADSHAW.
WILLIAM H. BROWN.
